(57) **CLAIM**

The ornamental design for a decorative light as shown and described.

DESCRIPTION

FIG. 1 is a front, right, and top perspective view of the decorative light, showing my design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and

FIG. 9 is a front, right, and top perspective view showing the decorative light in a position of use; and,
FIG. 10 is another front, right, and top perspective view showing the decorative light in a position of use.

The broken lines depict portions of the decorative light that form no part of the claimed design. The portions of FIGS. 9 and 10 shown in broken lines depict an environment of use for a decorative light and form no part of the claimed design. The double-dotted lines indicate symbolic breaks in the decorative light; the break lines and the appearance of any portion of the decorative light between the pairs of break lines form no part of the claimed design.
